UNITED STATES PATENT OFFICE.

PETER GUSTAF LEONARD, OF WEST TULSA, OKLAHOMA.

TUBING CATCHER.

Application filed August 19, 1927. Serial No. 213,996.

My invention relates to a tubing catcher, and more particularly to anchor or catcher means used for holding tubing in an oil well casing upon any sudden rupture or drop of 5 said tubing therein.

The main object of this invention is to provide a tubing catcher which will automatically and unfailingly anchor the tubing in the well casing upon any sudden drop of said tubing, and furthermore to provide it with means 10 and construct it so that the catching means will be automatically released upon a forceful pull on the tubing and the parts will be automatically returned and reset in their release or inoperative position. Another object 15 is to provide the gripping or catching means in the form of preliminary gripping means and main gripping means, the latter becoming effective upon the engagement of the former 20 with the well casing. A further object is to provide means for positively releasing both sets of gripping means and to return them into their inoperative position. Still another object is to construct the preliminary gripping 25 means in the form of eccentrics, and to provide means for resiliently mounting them, and for returning them into inoperative position and safely holding them therein, so as to automatically reset the gripping means after 30 they have been rendered operative upon a sudden drop in the well casing.

These and other objects and advantages are attained with my invention, as will become apparent from the following description, taken in connection with the accompanying drawings, in which,

Fig. 1 is an elevational view of my improved new tubing catcher, shown in its inoperative or release position, as initially entered into a well casing;

Fig. 2 is an elevational view thereof, during the beginning of a sudden drop of the tubing and catcher, showing the holding dogs retarded by the fall and the release lever arms 45 partly lowered with their attached eccentrics or preliminary gripping means beginning to bite into the well casing;

Fig. 3 is a horizontal cross-section, taken on line 3—3 of Fig. 1;

Fig. 4 is a vertical sectional view of the catcher, showing the parts at the end of the drop, when both sets of gripping means have become fully operative in engaging the well casing;

Fig. 5 is a horizontal cross-section, taken on line 5—5 of Fig. 4;

Fig. 6 is a vertical sectional view, showing the parts in position during the first part of a forceful pull on the tubing, after the lever arms have been raised and reset, like in Fig. 1, and have stressed the spring connection with the preliminary gripping means, while the releasing collar is beginning to knock loose the spreader cone from the main gripper slips to release them, whereupon the preliminary means are reset by their stressed spring means; during the final part of said pull; and

Fig. 7 is a detail view, showing the spring connection between one of the preliminary gripping means and its operating shaft and lever arm.

In the drawings I have illustrated my new and improved invention in its preferred form of construction, comprising a tubing section or central tube 10, which is adapted to be used in place of an ordinary tubing section. Guide collars or members 11, provided with guide collars 12, are threaded on the ends of tubing section 10, and may be used as coupling members, as indicated in the drawings. The other parts or elements are mounted around this central tube 10.

The entire gripping means or mechanism in this form of my invention comprises two sets of gripping means or elements, the preliminary gripping means and the main gripping means, whereof the former become first operative and thereby effect the movement of the latter into operation, so that both sets 90 firmly grip into the wall of a well casing 13 and hold the catcher and tubing sections positively suspended.

A supporting member or spider 14 is slidably mounted on tube 10, between the upper guide collar 11 and an annular flange 15 at the intermediate part of the tube. This spider is preferably constructed in the form of a sleeve having spaced flanges or ears 14' and 14'' arranged in pairs at opposite sides of the sleeve, for supporting and carrying the preliminary gripping means and operating means therebetween.

The preliminary gripping means comprises a member 16, preferably in the form of an eccentric or roller with teeth 16' eccentrically arranged around the axis, and this eccentric is pivotally mounted between a pair of said flanges 14' and 14'', as by means of a shaft 17' which is rotatable in said flanges. A lever arm 17 is fastened or fixed on the end of this shaft, for turning the shaft and therewith the

eccentric 16, which is resiliently mounted on the shaft by means of a spring 18 having one end 18' fastened to the shaft, and the other end 18'' bearing against the flattened side of 5 the eccentric 16. See Figs. 4 and 7. The lever arm thus provides means for operating the eccentric, and with the use of this spring is resiliently connected thereto, permitting movement of the arm and shaft relative to the eccentric, as becomes necessary when returning 10 the arm to inoperative position thereby stressing the spring, before the eccentric is released, as indicated in Fig. 6, for resetting this gripping means.

15 The means provided for positively holding or retaining the lever arms 17 and the connected eccentrics 16 in their inoperative or release position, as shown in Fig. 1, includes dogs or holding members 19, mounted with 20 pivot elements 20 on flanges 14', to swing vertically, each dog having a notch 19' for engaging the free end of an arm and holding it in its elevated or release position. A pin 21 may further be provided on one dog, and 25 a suitable notch on the opposite dog, for maintaining the dogs in similar vertical positions and assure simultaneous movement thereof.

The main gripping means comprises elongated wedge-like gripping elements or gripper slips 22, which are pivotally mounted on the spider, with pins 23 placed in lugs or ears 24 provided around the lower end of 30 the spider. These slips have suitable serrations or teeth 22' on their outer curved portions, for biting into the well casing, and are arranged to depend or hang normally free 35 from the well casing.

The means for spreading and moving these 40 slips to their operative position to grip the well casing comprises an inverted conical or tapered spreading member 25, which slidably surrounds tube 10 and has a pocket or annular chamber 26 in its broader upper end, 45 around tube 10, to receive the annular flange 15 of said tube therein, and thereby limits the upward movement of said member 25 on the tube. A spring 27, seated on the lower guide collar 11, engages under said member 25 50 and under a collar or disc 28 attached to the lower end of said member and normally retains the member in its elevated or release position, and this disc has lugs 29 thereon with outer curved portions for receiving the lower 55 curved ends of the gripper slips 22, thereby normally holding them spaced inwardly from the well casing.

I furthermore provide means for positively 60 releasing and again resetting both sets of gripping means, after they have been rendered operative and gripped the well casing, as through a sudden drop of the tubing sections, and this means will reset all of the gripping means automatically by a forceful 65 pull on the tubing sections, so as to render

my tubing catcher ready for any future drop and to again become operative and stop the same. This releasing and resetting means comprises flanges or ribs 30 provided on tube 10, above annular flange 15, and they are 70 movable vertically in slots or grooves 31 provided in spider 14, as shown in Figs. 3 to 6. These ribs 30 engage under the free ends of the lowered lever arms, when the parts are 75 in their operative position, as shown in Fig. 4, and upon a forceful pull on the tubing they raise and reset the arms into their initial operative position, as indicated in Fig. 6. Thereupon a member or collar 32, which is 80 provided on tube 10, above the lower guide collar 11, is raised with said tube to knock under the spreader cone and break it loose from the gripper slips 22; whereupon the eccentrics or preliminary gripping means are 85 automatically rotated and released by the continuing upward movement of the spider and by the tension of the springs 18, stressed by the previously raised lever arms, and reset in their initial inoperative position.

Operation of this improved tubing catcher.

The tubing catcher is connected to the tubing sections and lowered therewith into the well casing, with the elements or parts all placed in their release or inoperative positions, as indicated in Fig. 1 of the drawings. Upon any rupture and sudden drop of the tubing sections the dogs 19 are sufficiently retarded to free lever arms 17 which drop and move the eccentrics 16 into engagement with the well casing 13, as indicated in Fig. 2. Such engagement forces further turning and complete gripping position of these eccentrics, whereby the spider 14 and the gripper slips 22 carried thereby are stopped, and the descending spreader cone 25 forces said slips into positive operative position, as indicated in Fig. 4, thus placing all parts in their operative gripping positions.

To release the parts and reset them in their inoperative positions, a forceful pull on the tubing sections will slide the tube 10 upward in the spider and gripping elements, whereby ribs 30 on the tube will lift lever arms 17 into engagement with dogs 19 to be held thereby in the original inoperative position, as indicated in Fig. 6. In the meantime releasing collar 32 has been forcefully engaged under spreader cone 25 and is breaking it loose from the gripper slips 22, which thereupon return to their inoperative position, guided by the upper curved portions on lugs 29. Then during the final part of this upward pull the spider is moved upward thereby rotating and releasing the eccentrics 16, which are then further forced back into their release position by the springs 18 held under stress by the previously raised lever arms 17, thus automatically returning and resetting all parts 115 in their initial inoperative or release position,

as indicated in Fig. 1, all ready for any future drop of the tubing sections and the catcher, and to again become operative and stop the same.

5 Although I have disclosed my present invention herein in its preferred form, it may be noted that various changes in the construction may be resorted to and are intended to be comprehended hereby, as far as warranted 10 by the existing prior art.

What I claim as my invention and desire to secure by Letters Patent is:

1. A tubing catcher comprising eccentric gripping means, means fastened thereto for 15 positively turning the same, and means to hold both means in the inoperative position but to release the same upon sudden drop of the tubing for the gripping means to become operative.

20 2. A tubing catcher comprising rotatable gripping means, means resiliently connected therewith for actuating the same, and means for normally holding said actuating means with said gripping means inoperative, but to 25 release said actuating means upon a sudden drop of the tubing for rendering said gripping means operative.

30 3. A tubing catcher comprising eccentric gripping means, means connected therewith for actuating the same, means to hold both means inoperative but to release them upon sudden drop of the tubing for becoming operative, and means for returning and resetting the parts in their inoperative position.

35 4. A tubing catcher comprising gripping means, arms connected therewith for actuating the same, and means for normally engaging said arms and holding them with said gripping means inoperative but which upon 40 sudden drop of the tubing is retarded and releases said arms to render the gripping means operative.

45 5. A tubing catcher comprising a supporting member, gripping means rotatably mounted thereon, arms for actuating said means, and dogs on said member to normally hold said arms and means inoperative, but to raise upon sudden drop of the tubing and free said arms and render said gripping 50 means operative.

55 6. A tubing catcher comprising a spider, a shaft thereon and means for turning it, an eccentric gripper resiliently mounted on said shaft, and means for normally holding the shaft and is turning means with the gripper inoperative but to release them upon sudden drop of the tubing.

60 7. A tubing catcher comprising a central tubing, a supporting member slidable thereon, gripping means on said member and having arms fastened thereto whereby to positively move the same, means for holding said arms and gripping means normally inoperative but to release the arms automatically 65 upon a sudden drop of the tubing to render

the gripping means operative, and means on said tubing for positively moving said arms into engagement with said holding means, by a forceful pull on the tubing, for resetting the parts and again holding them inoperative.

70 8. A tubing catcher comprising a central tube, a supporting member slidable thereon, eccentric gripping means on said member, arms on said member for actuating said gripping means, means for holding said arms and gripping means inoperative but to release them upon a drop of the tubing to become operative, means on said tube to engage and return said arms to be again held by said holding means, upon a sudden pull on the tubing, and spring means connecting said gripping means resiliently with said arms permitting relative movement therebetween and final return of said gripping means.

75 9. A tubing catcher comprising a central tube, a spider slidable thereon, gripping means on said spider, arms on the spider for actuating said means, dogs for holding said arms in release position with the gripping means, said dogs being retarded to release the arms upon a drop of the tubing, and elements fixed on said tube to move upward therewith relative to the spider and raise said arms to the dogs to be held inoperative thereby, upon 80 a sudden pull on the tubing.

85 10. A tubing catcher comprising preliminary and main gripping means, means for rendering the preliminary and then the main gripping means operative upon a drop of the tubing, and means for returning and resetting said main means and also said preliminary means in their inoperative position automatically upon a forceful pull on the tubing.

90 11. A tubing catcher having a supporting member with preliminary and main gripping means pivotally mounted on the member, spreading means for the main gripping means, and means for holding the preliminary gripping means inoperative including 110 engaging elements which disengage upon a sudden drop of the tubing to render said preliminary means operative and permit the main gripping means to become operative on said spreading means.

115 12. A tubing catcher comprising a supporting member having eccentric gripping means thereon, main gripping means pivotally mounted on said member, arms for actuating said eccentric means, means for holding the arms and thereby said eccentric means inoperative but to release said arms and permit operation of the eccentric means upon a sudden drop of the tubing, thus retarding the drop of said supporting member 120 and the main gripping means, and means for spreading the main means to positively stop the drop of the tubing.

13. A tubing catcher comprising a central tube, a supporting member slidable on said

tube, preliminary and main gripping means pivotally mounted on said member, a spreading member on said tube for spreading said main means, arms on said supporting member 5 for actuating said preliminary means, means for holding said arms inoperative but release them upon a sudden drop of the tubing, whereby said arms move the preliminary means into engagement with a surrounding 10 well casing, and said main gripping means are forced outward by said spreading member, and means on said tube for moving said arms into the release position and for forcing the spreading means to release the main 15 gripping means.

14. A tubing catcher comprising a central tube, a supporting member slidable thereon, eccentric gripping means and main gripping means pivotally mounted on said member, 20 spreading means for said main means, arms for actuating said eccentric means, means to hold said arms but to release them for rendering said eccentric means operative upon a sudden drop of the tubing, thereby stopping 25 the drop of said supporting member and said main gripping means to make them operative on said spreading means, means on the tube for raising said arms, upon a forceful pull on the tubing, to return them for moving the 30 eccentric gripping means to inoperative position, and means on the tube to positively break loose the spreading means from the main gripping means.

15. A tubing catcher comprising a central 35 tube, a supporting member slidable on said tube, preliminary and main gripping means mounted on said member, spreading means on

the tube for spreading said main means, arms on said member for actuating said preliminary means, means for holding said arms normally inoperative but to release them upon a drop of the tubing to render the preliminary means operative, means on the tube for raising and resetting said arms upon a forceful pull on the tubing, means on the tube to break 40 loose the spreading means from the main gripping means for returning the same to the release position, and spring means between the preliminary gripping means and the arms being stressed by the arms for resetting these 45 gripping means in the initial position.

16. A tubing catcher comprising a central tube, a spider slidable on the tube, main gripping means and preliminary eccentric gripping means pivotally mounted on said spider, 55 arms on said spider for actuating said preliminary means, means for holding the arms inoperative, but to release them for moving the preliminary means to operative position, means for spreading the main means operative, after the preliminary means are operative and have stopped the spider, elements on the tube for engaging and resetting said arms automatically upon a pull on the tubing, a collar on the tube for releasing the spreading 60 means from said main means, and spring means connected to the eccentric preliminary means and to means on the arms for turning said eccentric means to release position upon 65 release of said main means.

In testimony whereof I have signed my name to this specification.

PETER GUSTAF LEONARD.
